STEAM PUMP

Filed Sept. 6, 1921

2 Sheets-Sheet 2

UNITED STATES PATENT OFFICE.

WILLIAM WILLSHAW, OF DES MOINES, IOWA.

STEAM PUMP.

Application filed September 6, 1921. Serial No. 498,930.

To all whom it may concern:

Be it known that I, WILLIAM WILLSHAW, a citizen of the United States, and a resident of Des Moines, in the county of Polk and 5 State of Iowa, have invented a certain new and useful Steam Pump, of which the following is a specification.

The object of my invention is to provide a steam pump of simple, durable and inexpensive construction for the efficient use of 10 steam for pumping water in mines and the like.

With this and other objects in view, my invention consists in the construction, arrangement and combination of the various 15 parts of my device, whereby the objects contemplated are attained, as hereinafter more fully set forth, pointed out in my claims, and illustrated in the accompanying drawings, in which:

Figure 1 shows a longitudinal, vertical, sectional view through a pump embodying my invention.

Figure 2 shows a vertical, sectional view 25 through one end of the valve controlling mechanism and the valve.

Figure 3 shows a similar sectional view of the other end of the valve controlling mechanism and the valve.

30 Figure 4 shows a top or plan view of the device with the valve and valve controlling mechanism removed.

Figure 5 shows a detailed, sectional view taken on the line 5—5 of Figure 4.

35 Figure 6 shows a detailed, sectional view taken on the line 6—6 of Figure 5.

Figure 7 shows a detailed, sectional view taken on the line 7—7 of Figure 8; and

40 Figure 8 shows a detailed, sectional view taken on the line 8—8 of Figure 7.

My improved pump, as illustrated in the accompanying drawings, comprises a body indicated by the reference numeral 10, preferably a casting, having the supporting 45 members 11 and having formed in its interior a hollow cylinder 12.

At the central part of the cylinder 12 from end to end thereof is a partition 13, such for instance, as is shown in Figure 1.

50 Mounted for slidable reciprocation within the cylinder 12 is a double-headed piston 14, having at its ends on opposite sides of the partition 13, the heads 15 and 16. The body of the piston 14, which connects the heads 55 15 and 16, is slidably mounted in a central

opening 17 in the partition 13. The piston heads 15 and 16 are preferably of the type having piston rings, which does away with the necessity for packing ordinarily used in pumps of this type.

On the top surface of the casting or body 10 is formed a flat valve seat 18 on which travels a slide valve 19, having in its under surface the recess 20, and having the central upwardly extending member 21.

60 In the valve seat 18 near the ends thereof are ports 22 and 23. The port 22 shown for instance in Figure 4, communicates with a passage 24 extending through the body 10 to the right-hand end of the cylinder 12 at the point 25, as illustrated in Figure 1. The port 23 communicates with a passage 26 in the body 10. The passage 26 communicates with the left-hand end of the cylinder 12, as at the point 27.

65 In the valve seat 18 between the ports 22 and 23 is an exhaust port 28. On top of the body 10 and covering the valve seat 18 is a body 28, which is hollow and has the removable ends 29.

70 In the interior of the body 28 near the ends thereof are formed cylinder portions 30 and 31, which terminate short of each other, as illustrated in Figure 1, and are open at their adjacent ends. Piston heads 32 and 33 connected by the connecting members 34 are mounted in the cylinder portions 30 and 31, as shown in Figure 1.

75 The piston members 34 have at their central portion a vertical guide 35 in which the extension 21 is slidably mounted.

80 Steam may be supplied to the interior of the body 28 from any suitable source through the opening 36.

85 The piston heads 32 and 33 are provided with small passages 37 and 38, illustrated for instance in Figures 2 and 3 and Figure 1.

90 Mounted in the wall of the casing or body 28 above the guide 35 is a transverse shaft 39, shown in Figures 1 and 8, having on its outer end a handle 40, and on its inner end an arm 41, projecting downwardly into the guide 35.

95 It will be seen that by swinging the handle 40, the piston comprising the heads 32 and 33 and the connecting members 34 which I may for convenience call the piston A may be reciprocated.

100 At the ends of the cylinder 12 are remov-

able end members 42 and 43, which have body portions 44 and 45 of substantial thickness, as illustrated for instance in Figure 1. In the body portions 44 and 45 are cylinders 46 and 47 terminating short of the inner ends of the body portions and covered at their outer ends by a plate or the like 49.

Slidably mounted in the cylinders 46 and 47 are pistons or the like 50 and 51. The pistons 50 and 51 have stems 52 and 53 slidably mounted in the body portions 44 and 45 and projecting into the ends of the cylinder 12, as shown in Figure 1.

Communicating with the end of the cylinder 46 nearest the cylinder 12 is an exhaust port 54 which may communicate with the main exhaust or with the air. Communicating with the cylinder 47 at the end thereof adjacent to the cylinder 12 is a similar exhaust port 55. A passage 56, shown in dotted lines in Figure 4, extends from the lower interior of the hollow body 28 at 57 to the outer part of the cylinder 46 at 58. A similar passage 59 extends from the interior of the casing 28 at 60 to the outer portion of the cylinder 47 at 61.

It may be noted at this point, that the parts in Figure 1 are viewed from one side of the device, while the parts in Figures 5 and 8 are viewed from the other side of the device.

A passage 62 extends from the right-hand end of the interior of the casing 28 at 63 to the inner end of the cylinder 47 at 64, as illustrated in Figures 1 and 4.

A passage 62^a leads from the lower interior of the member 28 at the left-hand side thereof at 63^a, as shown in Figure 4, to the inner end of the cylinder 46, as at 64^a.

At what may be called the front side of the body 10 near the middle thereof are horizontally spaced compartments 65 and 66. Above the compartments 65 and 66 is a compartment 67 (see Figure 8) and below the compartments 65 and 66 is a compartment 68.

The lower parts of the compartments 65 and 66 have valve seats 69 and 70, which cooperate with valves 71 and 72. The compartment 65 communicates by means of a passage 73 with the cylinder 12 on the right-hand side of the partition 13, as shown in Figure 1, and on the left-hand side of the partition, as the parts are illustrated in Figures 4, 5 and 8.

The compartment 66 communicates by means of a passage 74 with the other end of the cylinder 12.

Passages 75 afford communication through the valve seat 69 between the compartment 65 and the compartment 68. Passages 76 afford similar communication between the compartment 66 and the compartment 68.

Passages 77 afford communication between

the compartment 65 and the compartment 67 and passages 78 afford communication between the compartment 66 and the compartment 67.

For cooperating with the passages 77, a valve 79 is provided. A similar valve 80 cooperates with the passages 78.

Communicating with the compartment 68 is a water supply tube 81. A water discharge tube 82 leads from the compartment 67.

Secured to the valve 71, shown for instance in Figure 8, is a valve stem 83 slidably mounted in the partition between the compartments 65 and 67 and slidably mounted in the top of the compartment 67.

The stem 84 of the valve 72 is slidably extended upwardly through the partition between the compartments 66 and 67 and through the top of the compartment 67.

Mounted on the stem 83 between the partition 84^a, between the compartments 65 and 66 and the top of the compartment 67, is a sleeve 85. A similar sleeve 86 is similarly mounted on the stem 84. The valves 71 and 72 are yieldingly held seated by means of springs 87 and 88 arranged on the stems 83 and 84 between said valves and the partition 84^a.

Springs 89 and 90 mounted on the sleeves 85 and 86 between the valves 79 and 80 and the top of the compartment 67 yieldingly hold the valves 79 and 80 in their seated positions.

Assuming that the parts are in their positions, shown in Figure 1, and that steam is supplied through the opening 36 to the interior of the member 28, then the operation of the parts will be as follows:

The steam in the hollow member 28 will pass through the passage 26 to the outer left-hand end of the cylinder 12, as shown in Figure 1, for forcing the piston, which I have indicated generally by the reference character B, to the right.

The valves 51 and 50 are subject to the pressure of steam traveling through the passages 59 and 56 from the interior of the member 28.

The steam passing into the left-hand end of the cylinder 12, as shown in Figure 1, forces the piston B toward the right. This draws the water into the right-hand end of the cylinder 12 through the passage 73 from the compartment 65 and through the passages 75 from the compartment 68. The same movement of the piston forces the water out of the left-hand end of the cylinder 12, as shown in Figure 1 through the passage 74, the compartment 66, the passages 78 and 77, the compartment 67 to the discharge pipe 82.

The steam discharged from the right-hand end of the cylinder 12, as shown in Figure 1, passes through the passage 24 and the recess 20 to the discharge port 28^a.

It will be noted that the position of the valve 19 is such that the recess 20 therein stands above the ports 22 and 28^a, and that the piston A is at its right-hand position, 5 as illustrated in Figure 1.

When the piston B travels from its position shown in Figure 1 to its right-hand position, the head 16 strikes the stem 52, thereby forcing the piston 50, as shown in said figure, to the right; thereupon the piston 50 clears the opening 64 and the steam in the cylinder member 30 between the end of said cylinder member and the adjacent end of the piston A is allowed to exhaust through the 10 port 63^a, the passage 62^a the port 64, and the exhaust port 54.

The port 37 in the head of the piston A, near the port 63^a, is smaller than the port 63^a, so that thereupon the pressure of the 20 steam within the interior of the member 28 will force the piston A to the left from its position shown in Figure 1. The movement of the piston A carries with it, the valve 19 and moves the valve 19 from its positions 25 shown in Figures 1 and 3 to its positions shown in Figure 2. Thereupon the further passage of steam through the passage 26 will be prevented, while the passage 24 will be open to permit steam to pass therethrough to the right-hand end of the cylinder 12, as shown in Figure 1, for causing the return stroke of the piston B.

As soon as the head 16 leaves the stem 52, 35 the steam passing from the interior of the member 28 through the passage 59 and port 61 will move the piston 50 to the left, as shown in Figure 1, for closing the port 64. On the stroke of the piston B to the left, as 40 shown in said figure, the water in the right-hand end of the cylinder 12 will be forced out through the passage 73, the compartment 65, the passages 77 and the compartment 67 to the discharge pipe 82.

The same movement of the piston B draws 45 water into the left-hand end of the cylinder 12, as shown in Figure 1, through the passage 74, the compartment 66, the passages 76 and the compartment 68 from the intake pipe 81.

It may be noted that each end of the cylinder 12 is provided with a drain-cock 91.

The arm 41 and the handle 40 are to permit manual adjustment of the slide valve. 55 Sometimes when the machine is not in use, the slide valve or the double piston in the main cylinder will slide to improper positions with relation to each other. The slide valve can be easily adjusted manually to a proper position for starting the pump.

Changes may be made in the construction 60 and arrangement of the various parts of my improved steam pump without departing from the real spirit and purpose of my invention, and it is my intention to cover by

my claims, any modified forms of structure, or use of mechanical equivalents, which may be reasonably included within their scope.

I claim as my invention:

1. In a steam pump, a cylinder having a transverse partition therein, and having water passages adjacent to said partition, piston heads in said cylinder on opposite sides of said partition, a member connecting said piston heads, slidably mounted in said cylinder, an exhaust port leading from 70 partition, a steam chamber, cylinder members in the opposite ends thereof, piston heads in said last cylinder members, means for connecting said last named piston heads, 75 a slide valve operatively connected with said last means, steam passages extending from said steam chamber to the opposite ends of said first cylinder, an exhaust port leading from said steam chamber between said passages, said valve having a recess adapted in one of the positions of the valve to establish one of said passages and in another position of the valve to establish communication between said exhaust port and the other steam 80 passage, cylinders at the ends of said first cylinder having exhaust ports at their inner ends, pistons in said last described cylinders having stems slidably projected into the first cylinder, passages leading from 85 the interior of said cylinder members to the inner ends of said last-described cylinders, passages leading from said steam chamber to the outer ends of said last-described cylinders. 90

2. In a device of the class described, a cylinder having a transverse partition therein, and having water passages adjacent to said partition, piston heads slidably mounted in said cylinder on opposite sides of said partition, a member connecting said piston heads slidably mounted in said partition, a steam chamber, cylinder members in the opposite ends thereof, piston heads in said cylinder members, means for connecting said piston heads, passages extending from the opposite ends of said first cylinder to said steam chamber, a slide valve operatively connected with said last-named means, arranged to cooperate with said passages, an exhaust port leading from said steam chamber between said passages, cylinders at the ends of said first cylinder, having exhaust ports at their inner ends, pistons in said last cylinders having stems slidably projected into the first cylinder, passages leading from 100 the interior of said cylinder members to the inner ends of said last-described cylinders, passages leading from said steam chamber to the outer ends of said last-described cylinders. 105

3. In a device of the class described, a cylinder having a transverse partition therein, and having water passages adjacent to said partition, piston heads slidably mounted in said cylinder on opposite sides of said partition, a member connecting said piston heads, 110 passages extending from the opposite ends of said first cylinder to said steam chamber, a slide valve operatively connected with said last-named means, arranged to cooperate with said passages, an exhaust port leading from said steam chamber between said passages, cylinders at the ends of said first cylinder, having exhaust ports at their inner ends, pistons in said last cylinders having stems slidably projected into the first cylinder, passages leading from the interior of said cylinder members to the inner ends of said last-described cylinders, passages leading from said steam chamber to the outer ends of said last-described cylinders, said valve having a recess adapted in one of its positions to establish communication between the first described exhaust port and one of the steam passages to the first cylinder and in another position of the 115 first cylinder and in another position of the 120 first cylinder and in another position of the 125 first cylinder and in another position of the 130 first cylinder and in another position of the

valve to establish communication between said first described exhaust port and the other steam passage to the first described cylinder, water compartments communicating with said water passages to the first described cylinder, intake passages in said water compartments, spring-controlled valves for said intake passages, outlet passages from said water compartments, and spring-controlled valves for controlling said outlet passages.

3. In a device of the class described, a cylinder having a transverse partition therein, and having water passages adjacent to 15 said partition, piston heads slidably mounted in said cylinder on opposite sides of said partition, a member connecting said piston heads slidably mounted in said partition, a steam chamber, cylinder members in the opposite ends thereof, piston heads in said cylinder members, means for connecting said last-named piston heads, a slide valve operatively connected with said last means, passages extending from the opposite ends of 20 said first cylinder to said steam chamber, said valve being arranged to cooperate with said passages, an exhaust port leading from said steam chamber between said passages, cylinders at the ends of said first cylinder 25 having exhaust ports near their ends, pistons in said last-described cylinders having stems slidably projected into the first cylinder, passages leading from the interior of said cylinder members to the inner ends of said 30 last described cylinders, passages leading from said steam chamber to the outer ends of said last-described cylinders, said valve having a recess adapted in one of its positions to establish communication between the 35 first described exhaust port and one of the steam passages to the first cylinder and in another position of the valve to establish communication between said first described exhaust port and the steam passage to the 40 first described cylinder, and manual means for operating said slide valve.

4. In a steam pump, a cylinder having a transverse partition, a double-headed piston slidably mounted in said partition, a steam cylinder, passages connecting said steam cylinder with said first-named cylinder on opposite sides of said partition, a slide valve for controlling the flow of steam through said passages, a piston in the steam cylinder operatively connected with said valve, and means controllable by the movement of said first piston for controlling the flow of steam from said steam cylinder and the movement 55 of the second piston.

5. In a steam pump, a cylinder having a transverse partition, a double headed piston slidably mounted in said partition, a steam cylinder, passages connecting said steam cylinder with said first named cylinder on opposite sides of said partition, a slide valve 60 for controlling the flow of steam through said passages, a piston in the steam cylinder operatively connected with said valve, means controllable by the movement of said first piston for controlling the flow of steam 65 from said steam cylinder and the movement of the second piston, and manual means for actuating the second piston.

6. In a steam pump, a cylinder having a transverse partition, a double headed piston slidably mounted in said partition, a steam cylinder, passages connecting said steam cylinder with said first named cylinder on opposite sides of said partition, a slide valve 70 for controlling the flow of steam through said passages, a piston in the steam cylinder operatively connected with said valve, and means controllable by the movement of said first piston for controlling the flow of steam 75 from said steam cylinder and the movement of the second piston, said means including cylinders having communication near their ends with the steam cylinder and outlet openings and pistons in the last described 80 cylinders.

Des Moines, Iowa, December 3, 1920.

WILLIAM WILLSHAW.
